UNITED STATES PATENT OFFICE

2,209,822

PUFF IRON

Charles A. Lindemann, Bridgeport, Conn., assignor to General Electric Company, a corporation of New York

Application August 9, 1938, Serial No. 223,868

6 Claims. (Cl. 38—66)

The present invention relates to puff irons for ironing machines of the type having cooperating pressing members which are brought into engagement to iron material placed therebetween.

5 In ironing machines of this type there are certain types of irregular material, such as ruffles and the like, which are not conveniently ironed by placing between the pressing members. Material of this type is more readily ironed by drawing the material across a heated surface of small dimensions, which is called a puff iron.

10 The object of my invention is to provide an improved construction and arrangement in a puff iron which is carried within the edges of one of the pressing members when not in use and which is extended to a position projecting beyond the pressing member when in use.

15 In the accompanying drawing, Fig. 1 is an end elevation of an ironing machine equipped with a puff iron embodying my invention; Fig. 2 is a top plan view, partly broken away, of the heated shoe showing the manner of supporting the puff iron; Fig. 3 is a view of the handle for moving the shoe into and out of register with the other pressing member; Fig. 4 is an end elevation of the shoe, and Fig. 5 is a diagrammatic view showing the manner in which the puff iron is pressed against the heated shoe.

20 The invention is shown applied to an ironing machine of the type shown in application Serial No. 750,620, filed Oct. 30, 1934. In this construction an electrically operated pressure developing mechanism is contained within a cylinder 1 having a flange 2 supporting the cylinder on the top 25 3 of a table. Within the cylinder is a piston on the top of which is mounted a suitably padded buck 4. On the lower end on the cylinder is pivoted an arm 5 which supports a heated shoe 6. The shoe is moved into and out of register with the buck by means of a handle 7 supported on the front of the shoe. The rearward movement of the arm 5 is cushioned by a spring 8 connected to toggle links 9 and 10 which are respectively pivoted to the arm and to the cylinder.

25 40 The shoe is preferably made of metal, such as aluminum, and is heated by electric heating elements 11 clamped in grooves 12 in the upper surface of the shoe by clamps 13. The upper surface of the shoe is enclosed by a sheet metal cover 14 which fits against the outer edge of a rib 15 extending around the edge of the shoe. On the front edge of the shoe are fixed wire guards 16 which prevent the operator from being burned by accidental contact with the shoe.

45 50 55 The handle 7 is supported on the shoe by means

of a frame comprising bars 17 and 18 connected by a cross-member 19 which has spaced ears 20 projecting from the upper side thereof through openings of the shoe cover 14. The bars 17 and 18 are secured to the upper side of the shoe by means of screws 21, 22, 23 and 24. The bars 17 and 18 have clearance openings 25 around the screws 22, 23, and 24 so that the frame can have a limited pivotal movement about the screw 21. This limited pivotal movement is used to control the electric circuit to the pressure developing mechanism for the ironer. The complete circuit to the pressure developing mechanism is not shown. It includes a conductor 26 connected to the stationary contact 27 of a switch 28 fixed to the upper side of the shoe and a conductor 29 connected to a flexible conducting strip 30 carrying the movable contact 31 of the switch. The contacts are biased to the closed position by a spring strip 32 which engages the strip 30. Upon 20 counterclockwise movement of the handle carrying frame an ear 33 on the bar 18 engages a button 34 on the strip 30 and moves the strip to a position in which the movable contact 31 is separated from the stationary contact 27 thereby 25 breaking the circuit to the pressure developing mechanism.

20 25 30 35 The handle 7, which is made of molded insulating material, is pivoted on screws 35 which are threaded in the ears 20. Recessed in the handle is a detent 36 which cooperates with a member 37 fixed to the front edge of the shoe to hold the handle in the position shown in Fig. 3. The detent is urged by a coil spring 38 to the position shown. The detent is moved out of engagement with the member 37 by means of a button 39 carried on a stud 40 projecting through a slot 41. Upon moving the button 39 to the right, as viewed in Fig. 3, the detent is moved clear of the member 37 and the handle may thereafter be pivoted on the screws 35 to a position resting on the top of the shoe cover 14. In this position the handle does not project from the shoe. When the ironer is to be used the handle is pivoted to the position shown in Fig. 3, and is 40 held in this position by the detent.

35 40 45 50 55 At one end of the shoe is a puff iron 42 which is slidably carried on the upper surface of the shoe beneath the shoe cover 14. The puff iron is made from a bar of metal and has a working surface 42' at the front end which is spaced from the upper surface of the shoe and has a part 43 at the rear of the working surface which is slid- able in a groove 44 in the upper surface of the shoe. The working surface 42' of the puff iron 55

has rounded corners which provide a smooth surface across which the material to be ironed may be drawn. The puff iron is moved between the extended and retracted positions by a resilient wire lever 45 which has a hooked end 46 extending through an opening 47 in the bar 18 and providing a pivotal support for the lever. The lever extends from the bar 18 transversely across the part of the puff iron remaining within the shoe and through an opening 48 in a boss 49 on the puff iron and out through a cam slot 50 in shoe cover 14, terminating in a handle 51. As shown in Figure 4, the slot 50 is provided with downwardly inclined portions 52 and 53 respectively at the front and rear ends. When the lever rests in one of these inclined portions the outer end of the lever is pressed downward below the level of the opening 48 in the boss 49 and the rear portion of the puff iron is accordingly pressed into intimate contact of the upper surface of the shoe. The manner in which this pressure is obtained is illustrated diagrammatically in Figure 5, the lever being shown at the front of the inclined portion 52 of the slot 50. This corresponds to the extended position of the puff iron in which the working surface 42 projects beyond the front edge of the shoe in a readily accessible position. The inclined portion 53 of the slot 50 is provided with a detent notch 54 which holds the lever in the retracted position. As the lever is moved from the retracted position, shown in full lines in Figure 2, to the extended position, shown in dotted lines, the handle 51 swings further away from the end of the shoe. The operator, therefore, has less chance of being burned while moving the puff iron.

When the puff iron is in the extended position, it is desirable that operation of the pressure developing mechanism be prevented. This is accomplished by the pivoting of the lever on the head of the screw 24 which serves as a fulcrum. When the lever 45 is in the dotted line position of Fig. 2, the bar 18 is moved to a position in which the tongue 33 separates the contacts 27 and 31 opening the circuit to the pressure developing mechanism and preventing operation thereof.

What I claim as new and desire to secure by Letters Patent of the United States, is:

1. In an ironer having a shoe, a puff iron carried within the edges of the shoe and having a working surface movable to a position projecting beyond an edge of said shoe when in use and having a part to the rear of said working surface remaining within the edges of the shoe, a lever having a handle projecting beyond the shoe and having a portion within the shoe extending transversely across said part of the puff iron remaining within the shoe, means mounting the lever on the shoe for swinging movement over the shoe in the direction of movement of said puff iron, and interengaging portions on said lever and said part of the puff iron whereby the puff iron is moved between the extended and retracted positions by the swinging movement of the lever.

2. In an ironer having a shoe, a puff iron carried within the edges of the shoe and having a working surface movable to a position projecting beyond an edge of said shoe when in use and having a part to the rear of said working surface remaining within the edges of the shoe, a lever for moving the puff iron on the shoe, and means carried by the shoe and engaging the lever for pressing the lever against the part of the puff iron to the rear of the working surface whereby said part of the puff iron is pressed against the shoe.

3. In an ironer, a shoe, a cover for the upper surface of the shoe, a puff iron slidably carried on the upper surface of the shoe beneath the cover and movable between a retracted position within the edges of the shoe and an extended position having a working surface projecting beyond an edge of the shoe, a lever for moving the puff iron between the extended and retracted positions projecting through a cam slot in the shoe cover, and a connection between the lever and the puff iron whereby the puff iron is pressed against the upper surface of the shoe by the action of the cam slot on the lever.

4. In an ironer having a shoe, a puff iron carried within the edges of the shoe and having a working surface movable to a position projecting beyond an edge of said shoe when in use and having a part to the rear of said working surface remaining within the edges of the shoe, a lever mounted on the shoe for movement over the shoe for moving the puff iron between the extended and retracted positions, means carried by the shoe and engaging the lever for exerting force on the lever for effecting pressing of the part of the puff iron to the rear of the working surface against the shoe.

5. In an ironer having a shoe, a puff iron carried within the edges of the shoe and having a working surface movable to a position projecting beyond an edge of said shoe when in use and having a part to the rear of said working surface remaining within the edges of the shoe, a lever mounted on the shoe for movement over the shoe for moving the puff iron between the extended and retracted positions, and cam means engageable by the lever during its movement for effecting pressing of the part of the puff iron to the rear of the working surface against the shoe.

6. In an ironer having a shoe, a puff iron carried within the edges of the shoe and having a working surface movable to a position projecting beyond an edge of said shoe when in use and having a part to the rear of said working surface remaining within the edges of the shoe, a lever mounted on the shoe for movement over the shoe for moving the puff iron between the extended and retracted positions, and carried in the shoe for pressing the lever against the puff iron whereby the part of the puff iron to the rear of the working surface is pressed against the shoe.

CHARLES A. LINDEMANN.

CERTIFICATE OF CORRECTION.

Patent No. 2,209,822.

July 30, 1940.

CHARLES A. LINDEMANN.

It is hereby certified that error appears in the printed specification of the above numbered patent requiring correction as follows: Page 1, first column, line 8, for "betwen" read --between--; and second column, line 4, for "of" read --in--; page 2, first column, line 2, for "wihch" read --which--; and second column, line 58, claim 6, before "carried" insert --means--; and that the said Letters Patent should be read with this correction therein that the same may conform to the record of the case in the Patent Office.

Signed and sealed this 3rd day of September, A. D. 1940.
